CLAIM

The ornamental design for a set of driver's gloves, as shown and described.

DESCRIPTION

FIG. 1 is a bottom left front view of the set of driver's gloves according to my new design;

FIG. 2 is a front view thereof;

FIG. 3 is a back view thereof;

FIG. 4 is a left side view thereof;

FIG. 5 is a right side view thereof;

FIG. 6 is a bottom view thereof; and,

FIG. 7 is a top view thereof.

Although shown in the context of a left hand glove, the present invention is also incorporated in a right hand glove. The broken lines represent portions of the article and form no part of the claimed design.
